RUDDER PEDAL ADJUSTING MECHANISM

William A. Pickens, San Diego, and Freeman D'Vincent La Jolla, Calif., assignors to Consolidated Vultee Aircraft Corporation, San Diego, Calif., a corporation of Delaware

Application October 11, 1946, Serial No. 702,688

2 Claims. (Cl. 244—86)

1

This invention relates to airplane rudder pedals and more particularly to adjusting mechanism therefor.

An object of the present invention lies in the provision of improved adjusting mechanism for rudder pedals whereby the operating position of the rudder pedals within the airplane may be readily changed.

Another object of the invention is to provide improved means for adjusting the operating position of rudder pedals to accommodate pilots having different leg lengths.

An additional object of the invention resides in the provision of improved adjusting means for changing the operating position of two co-acting rudder pedals simultaneously without affecting the position of the control cables leading to the rudder.

A further object is the providing of improved adjusting means for changing the operating position of rudder pedals, which adjustment may be made while the airplane is in flight and without interfering with the operation of the rudder pedals.

Other objects and features of the invention will be readily apparent to those skilled in the art from the following specification and appended drawings illustrating certain preferred embodiments in which:

Figure 1 is a plan view of a rudder control system embodying the rudder pedal adjusting mechanism of the present invention;

Figure 2 is a top plan view of the adjustment mechanism according to the present invention;

Figure 3 is a side elevational view;

Figure 4 is a top plan view, enlarged, of the adjusting mechanism with certain parts broken away for clarity of disclosure; and

Figure 5 is a sectional view showing the gearing system employed by the adjusting mechanism of the present invention.

Referring more particularly to the drawings, there is shown in Figure 1 a pair of rudder pedal assemblies 10 and 11 which are adapted to be disposed in the pilot's compartment in position for operation by an operator and connected by control cables 12 and 13 to a usual rudder 14, with the control cable 12 passing over a main pulley 15 and suitable pulleys 16, and the control cable 13 passing over a main pulley 17 and suitable pulleys 18. Each of the rudder pedal assemblies 10 and 11 are adapted individually to operate the rudder 14.

For effecting a change in the operating positions of the rudder pedal assemblies 10 and 11

2

to adapt it to the length of the leg of the pilot there are provided adjusting assemblies 21 and 22 which are supported on a usual bulkhead or other fixed portion of the fuselage. Each of the rudder pedal assemblies 10 and 11 are adapted through their respective associated adjusting assemblies 21 and 22 to be individually and separately adjusted as desired.

Since each of the rudder pedal assemblies 10 and 11 and their associated adjusting assemblies 21 and 22 are similar in construction but one of them will be described, which here will be the rudder pedal assembly 10 and its adjustment assembly 21.

The rudder pedal assembly 10 embodies a pair of usual pedals or foot treads 23 and 23a each fixedly mounted on and between a pair of spaced elongated vertical or side members 24 and 25 which in turn are pivotally mounted at their upper ends to a bracket 26 supported by a generally U shaped fixed channel member 27. With this construction the pedals 23 and 23a are adapted to be swingingly moved, this pivotal movement being about the pivot of members 24 and 25.

The adjusting mechanism 21 for rudder assembly 10 comprises a generally triangularly shaped bracket 28 which is rigidly attached to the aircraft structure in any well known manner. The bracket 28 includes two horizontally spaced arms 29 and 30 with the arm 30 being provided with a flange portion 31, which flange is riveted or otherwise secured to a brace member to thereby supply a further support for bracket 28.

Disposed between the spaced arms 29 and 30 is a control quadrant or pivotal member 32 having a winged portion 33 and an elongated portion 34 extending centrally therefrom. This central portion 34 is pivotally mounted at its end 35 upon a vertical shaft 36 which is supported at the ends of arms 29 and 30. An end of control cable 12 is securely attached to a projection 37 on portion 34 of quadrant 32. Cable 12 is led from this point of attachment over the periphery of quadrant 32, lying in a groove (not shown) provided therein, and passed over pulley 15 and then to the rudder 14. A mounting bracket 38 supports pulley 15 adjacent quadrant 32. Rotative movement of quadrant 32, about the pivot provided by shaft 36, by rudder pedal 23 through means to be hereinafter described will effect movement of cable 12. To secure movement of the opposite cable 13 there is provided a link member 41 which operatively con-

ncts quadrant 32 of adjusting assembly 21 to similar quadrant 32a of adjusting assembly 22 to which is attached cable 13 in a manner similar to the attachment of cable 12 to quadrant 32. Therefore when quadrant 32 is actuated by rudder pedal 23a, in a counter-clockwise direction, as viewed in Figure 2, connecting link 41 will also be actuated to effect movement of quadrant 32a, counter-clockwise, thereby moving cable 13 to operate rudder 14.

A pair of oppositely directed lever members 42 and 43 are also pivoted upon shaft 36, the lever members 42 and 43 respectively being provided with horizontally spaced arms 42a and 42b, and 43a and 43b with one arm of each being located on a side of the extended portion 34 of quadrant 32 and at the point where it is pivotally mounted on this same shaft 36. Horizontally disposed connecting rods 44 and 45 interconnect the lever members 42 and 43 respectively to rudder pedals 23 and 23a, with the ends 44a and 45a of the rods 44 and 45 pivotally connected to levers 42 and 43 and with their opposite ends pivotally connected to the vertical or side members 25 of the rudder pedals 23 and 23a.

Carried by the extended portion 34 of quadrant 32 is a shaft 46 the ends of which are smooth faced and with the portion therebetween threaded to provide a worm. An annular bearing surface 47 provided on extended portion 34 of quadrant 32 supports one end of worm 46, with the opposite end of the worm fitting into a recess 48 provided by the winged portion 33 of quadrant 32.

Supported by the worm 46 for longitudinal movement thereon is an internally threaded nut-like member 51. Elongated link members 52 and 53 interconnect the two lever members 42 and 43 and the nut-like member 51, one end of each link member 52 and 53 being pivotally attached to a lever member and the other end pivotally attached to traveling member 51. Movement of nut-like member 51 on worm 46 will, through the connections described, effect pivotal movement of the lever members 42 and 43, as will be further hereinafter described.

Mounted on the right-hand end of the worm 46, as viewed in the drawings, is a bevel gear 54, the bevel gear 54 being rigidly secured on worm 46 by a pin or in any other well known manner. Rotatively mounted on shaft 36 is an idler bevel gear 55 having teeth 56 provided on its under surface which mate with bevel gear 54 and teeth 57 on its upper surface which mate with a bevel gear 58. The latter bevel gear 58 is carried by a shaft 61 which in turn is rotatively mounted on upwardly extending spaced lugs 62 and 63 which are integral with arm 29 of supporting bracket 28. Tubular member 64 is secured to an end of shaft 61 and forms a continuation thereof. Tubular member 64 passes through an opening in a support bracket 65 mounted on channel member 27 and into the pilot's compartment. A knob 66 is secured to the end of tubular member 64 to facilitate manual rotation of tubular member 64 and shaft 61 and thereby effect rotation of bevel gear 58.

The operation of the invention will now be described:

When the pilot or operator of an aircraft equipped with the present invention desires to adjust the operating position of a pair of rudder pedals 23 and 23a to a position that is more comfortable and better adapted to the length of

his legs, it is necessary for him only to rotate knob 66 which will effect a movement of the rudder pedals forward or aft, dependent on the direction of rotation of the knob; rotation of knob 66 is continued until the rudder pedals are disposed in the desired position.

As is obvious from the drawings, rotation of knob 66 will rotate shaft 61 and bevel gear 58 affixed thereon. Rotation of bevel gear 58 will 10 effect rotation of the idler gear 55 which mates with bevel gear 58; the moving idler gear 55 will then cause rotation of bevel gear 54 carried by worm 46 to thereby effect rotation of worm 46 with a resultant longitudinal movement of the nut-like member 51 upon the worm, with forward or aft longitudinal movement being dependent on the direction of rotation of the worm 46. The nut-like member 51 moving along the worm 46 will effect pivotal movement of the levers 42 and 43 about shaft 36 through means of the connections therewith afforded by the link elements 52 and 53. The levers 42 and 43 being connected to the vertical members 25 of the rudder pedals 23 and 23a by connecting rods 44 and 45 will, 20 when themselves rotated about their common pivot 36 by traveling member 51, cause a pivotal movement of the rudder pedals to the desired new position. Movement of the traveling member 51 forwardly on worm 46, that is away from the pilot, will therefore rotate levers 42 and 43 about their common pivot 36 to rotate vertical members 25 about their pivots to move the rudder pedals 23 and 23a forwardly and away from the pilot thereby placing them in operating position 25 for the longer legged pilot. Movement of the traveling member 51 aft (toward the pilot) on the worm 46 will rotate levers 42 and 43 in the opposite direction to effect movement of the rudder pedals 23 and 23a toward the pilot, thereby 30 placing them in position to be operated by a shorter legged pilot. The forward and aft positions that may be assumed by levers 42 and 43 are indicated in dotted outline in Figure 4.

It is here specifically pointed out that the adjustment of the operating position of the rudder pedals may be made when the airplane is in flight and even though flight conditions may be such that one of the rudder pedals is being held in a forward position, as when a strong side wind is present.

Adjustment of the operating position of the rudder pedals 23 and 23a may be secured also by electrical means if so desired. The alternate arrangement involves the substitution of an electric motor 67, shown in dotted outline in Figure 3, for the knob 66 and the long tubular element 64. The electric motor 67 will be arranged to drive directly shaft 61 and rotate bevel gear 58 and thereby effect the adjustment of the rudder pedals. The motor 67 should be of the reversible type to permit rotation of bevel gear 58 in either direction to obtain fore and aft adjustment of the rudder pedals. The motor 67 can be controlled by a switch, not shown, disposed in the 65 pilot's compartment.

With the rudder pedals 23 and 23a disposed in the operating position best suited to the legs of the pilot, movement of rudder 14 in a desired direction may then be secured by movement of 70 the appropriate rudder pedal 23 or 23a. Movement of the rudder pedals 23 and 23a will effect pivotal movement of the quadrant 32 which will actuate the cables 12 and 13 to move the rudder 14. For example, movement of rudder pedal 23 by the foot of the operator will move connecting

rod 44 to rotate lever 42 about its pivot 36. Lever 42 will through link member 52 apply force on the nut-like member 51 to thereby rotate quadrant 32 in a counter-clockwise direction about shaft 36 to pull on cable 12 to rotate the rudder 14 clockwise. To effect movement of the rudder 14 in the opposite direction rudder pedal 23a is moved forward to actuate connecting rod 45 to pivot lever 43 and effect rotative movement of quadrant 32 in a counter-clockwise direction thereby moving connecting link 41 downwardly to effect counter-clockwise movement of quadrant 32a to provide a pull on cable 13 which will move rudder 14 counter-clockwise. It is understood that rudder assembly 11 may be omitted and only one set of rudder pedals provided for effecting operation of the rudder 14. In this case the cable 13 would be connected to quadrant 32 at a point opposite the point of attachment of cable 12, so that rotative movement of quadrant 32 in opposite directions will provide a pulling force on first one cable and then the other.

While certain preferred embodiments of the invention have been specifically disclosed it is understood that the invention is not limited thereto as many variations will be readily apparent to those skilled in the art and the invention is to be given its broadest possible interpretation within the terms of the following claims.

What is claimed is:

1. Rudder control mechanism comprising a pair of co-acting rudder pedals, means pivotally mounting said rudder pedals in operating position, a quadrant member, a shaft on which said member is pivotally mounted, rudder control cables operatively connected to said pivotal member for movement thereby, a pair of lever members pivotally mounted on said shaft, connecting means pivotally secured to said lever members and said rudder pedals to join said lever members to said rudder pedals to permit the latter to effect pivotal movement of the former, an elongated externally threaded member mounted for rotative movement on said quadrant and bodily movable with said quadrant, a nut member carried by said threaded member and movable longitudinally thereupon on rotation of said threaded member, link means pivotally attached at the ends thereof to said lever members and said nut member to interconnect said lever members with said movable nut member whereby said lever members when actuated by said rudder pedals move said quadrant member to operate said rudder control cables, a bevel gear carried by said threaded member, a gear mounted on said shaft which mounts said quadrant member and said pair of lever members, said gear mating with said bevel gear and being adapted to effect movement thereof to rotate said threaded member to move 45

the nut member carried thereon relative to said quadrant member to actuate said lever members to change the operating position of said rudder pedals, and means actuatable from a remote point to operate said gear.

2. Rudder control mechanism comprising a pair of co-acting rudder pedals, means pivotally mounting said rudder pedals in operating position, a quadrant member, a shaft on which said member is pivotally mounted at one end, rudder control cables operatively connected to said pivotal member at the end opposite its pivotal mounting for movement thereby, a pair of lever members, pivotally mounted at one of their ends on said shaft, connecting means pivotally secured to said lever members and said rudder pedals to join said lever members to said rudder pedals to permit the latter to effect pivotal movement of the former, an elongated externally threaded member, spaced bearing surfaces provided by said quadrant for supporting said threaded member for rotative movement on said quadrant, a nut member carried by said threaded member and movable longitudinally thereupon on rotation of said threaded member, link means pivotally attached at the ends thereof to said lever members and said nut member to interconnect said lever members with said movable nut member whereby said lever members when actuated by said rudder pedals move said quadrant member to operate said rudder control cables, a bevel gear carried by said threaded member, an idler gear mounted on said shaft which mounts said quadrant member and said pair of lever members, said idler gear mating with said bevel gear and being adapted to effect movement thereof to rotate said threaded member to move the nut member carried thereon relative to said quadrant member to actuate said lever members to change the operating position of said rudder pedals, a second bevel gear adapted to move said idler gear, and manually operable means for actuating said second bevel gear from a remote position.
